Primary Examiner — Clint A Samuel(74) *Attorney, Agent, or Firm* — Frost Brown Todd LLC; Dennis S. Schell**CLAIM**

The ornamental design for a floodlight with visor, as shown and described.

DESCRIPTION

FIG. 1 is a front perspective view of a floodlight with visor, showing the new design;

FIG. 2 is a rear perspective view of the new design;

FIG. 3 is a front elevational view of the new design;

FIG. 4 is a rear elevational view of the new design;

FIG. 5 is a left-side elevational view of the new design;

FIG. 6 is a right-side elevational view of the new design;

FIG. 7 is a top plan view of the new design; and,

FIG. 8 is a bottom plan view of the new design.

The broken lines shown in the drawings are included for the purpose of illustrating unclaimed portions of the floodlight with visor and form no part of the claimed design.
